CARPET CLEANING APPARATUS

Gilbert G. Cyphert, 4320 N. 14th St.,
Phoenix, Ariz. 85014

Filed Aug. 12, 1974, Ser. No. 496,408

Term of patent 14 years

Int. Cl. D15—05

U.S. Cl. D7—167

FIG. 1 is a front perspective view of a carpet cleaning apparatus showing my new design;

FIG. 2 is a rear elevational view thereof, shown with the hose removed for ease of illustration;

FIG. 3 is a fragmentary side elevational view thereof, showing the solution tank and related apparatus on an enlarged scale;

FIG. 4 is a side elevational view thereof, showing the head portion on an enlarged scale and shown with the handle and hose elements broken away for ease of illustration; and

FIG. 5 is a bottom plan view of the head portion, with the handle and hose elements broken away for ease of illustration.

I claim:

The ornamental design for a carpet cleaning apparatus, as shown and described.
